ROTATABLE CASEMENT WINDOW ADJUSTER

Lawrence G. Zarbock, Dayton, Ohio, assignor to
Standard-Thomson Corporation, Dayton, Ohio,
a corporation of Delaware

Application March 9, 1949, Serial No. 1,303

Term of patent 14 years

(Cl. D10—10)

To all whom it may concern:

Be it known that I, Lawrence G. Zarbock, a citizen of the United States, residing at Dayton, in the county of Montgomery, State of Ohio, have invented a new, original, and ornamental Design for a Rotatable Casement Window Adjuster, of which the following is a specification, reference being had to the accompanying drawing, forming a part thereof.

In the drawing:

Fig. 1 is a top plan view of a rotatable casement window adjuster showing my new design; Fig. 2 is a front elevational view of the adjuster; and Fig. 3 is an end elevational view of the adjuster.

I claim:
The ornamental design for a rotatable casement window adjuster as shown.

LAWRENCE G. ZARBOCK.
